UNITED STATES PATENT OFFICE.

HARRY J. THOMPSON, OF NEW YORK, N. Y.

MOLDING APPARATUS.

1,234,418.

Specification of Letters Patent. Patented July 24, 1917.

Application filed July 31, 1914. Serial No. 854,337.

To all whom it may concern:

Be it known that I, HARRY J. THOMPSON, a citizen of the United States, residing at New York, in the county of New York and 5 State of New York, have invented a new and useful Molding Apparatus, of which the following is a specification.

The present invention relates to improvements in molding apparatus, and more especially to an apparatus for molding from paper pulp or fiber articles provided with a plurality of cup shaped members, one object of the invention being the provision of means whereby the fiber is caused to adhere 10 to the surface of the male molding member and by means of which the same is released therefrom when between the male and female molding members, the release effect being exerted equally upon each of the cup 15 shaped members of the fabric so as to release the same from the surface of the male member without tearing or distorting the fabric.

In molding various shapes from fiber, either newspaper or wood pulp, it has been 20 a difficult matter to remove the completed member from either the female or male mold without destroying the fabric, for the reason that the fabric is so soft and plastic and also 25 for the reason that the cup shaped male or 30 female member is not readily withdrawn due to the sliding adhering action the mold has to a certain portion of the cup of the fabric that tends to prevent the easy withdrawal. It has been found in practice, that 35 the best possible method of releasing the molded fabric from the male member to which it has the greatest tendency to adhere, is to perforate the member so that an air blast may be delivered from the cup 40 shaped portion thereof at the sides and against the molded fabric, the male member being withdrawn only a slight distance from the female member so that the air will have only the necessary pushing action against 45 the fabric without distorting or tearing it.

In practice, the distance necessary to perform the desired disengagement of the fiber from the male member is not over one thirty-second of an inch; that the male member is 50 moved that distance after coöperation with the female member. In directing the air blast against the molded article for the purpose of stripping it from the male mold member, it has been found necessary, in order 55 to effect a clean separation of the article from the mold member, to first direct the

air blast against the open end portion of the molded article and in the direction of the opposite end of said article so that the article will be stripped progressively from one end toward the other thereof. In this manner, danger of rupturing the article or distorting it is eliminated and quick and clean separation of the article from the male member of the mold is insured. The perforated 60 portions of the male members not only act as air blast directing means but also permit air to be sucked therethrough to suck or draw the fiber against such member to coat the surface thereof before the same is properly molded in the female member. The female mold is designed to have imparted thereto a half revolution so as to present the upper mold receiving surface upside down in a horizontal plane and thus permit the completed fabric to fall therefrom with the cup shaped portion opening downwardly to produce a parachute effect that reduces the impact from the fall of the fabric from the reverse surface of the female member to the 70 conveying belt. It has been found that the distance of fall, which is approximately fourteen inches, will not in any way damage the finished fabric by contact with the conveyor belt. 75

With the foregoing and other objects in view which will appear as the description proceeds, the invention resides in the combination and arrangement of parts and in the details of construction hereinafter described 80 and claimed, it being understood that changes in the precise embodiment of the invention herein disclosed can be made within the scope of what is claimed without departing from the spirit of the invention. 85

In the drawings—

Figure 1 is an end elevation showing the complete apparatus, the male member being in the position it assumes just prior to the introduction within the vat or after having 100 been removed therefrom and before being moved to coöperate with the female mold member.

Fig. 2 is a top plan view showing the greater portion of the mechanism as illustrated in Fig. 1, some of the levers and air conducting pipes being removed. 105

Fig. 3 is a top plan view of the male mold.

Fig. 4 is a side elevation thereof. 110

Fig. 5 is a top plan view on an enlarged scale with a portion of the male molding

member, showing in dotted lines one of the sections thereof by means of which one sheet of the fabric is formed.

Fig. 6 is a section taken on line 6—6 of Fig. 5.

Fig. 7 is an enlarged detail sectional view of one of the air directing members carried by the male molding member.

Fig. 8 is a top plan view of the same.

Fig. 9 is a plan view of one sheet of the completed fabric.

Referring to the drawings, the numeral 1 designates the pulp holding vat, while 2 indicates the male molding member which is adapted to have both vertical and horizontal movements, the same being supported by means of the flexible connections or chains 3 to the hooked end 4 of the piston of the pneumatic motor 5 which is carried by the truck 6 and supported by the two beams 7 which constitute the main support for the apparatus.

Mounted upon the upper face of the beams 7 is the reciprocating motor 8, whose piston 9 is connected at opposite ends to the cables 10 and 10^a whose other terminals are connected to the lugs 11 and 11^a to the reciprocating motor 5, said cables being passed over the guiding pulleys 12 and 12^a journaled between the beams 7. Thus as the motor 8 is operated, the truck 6 is moved along the beams 7 horizontally so that the male member 2 may be moved from above the vat to a point above the female mold member 18, whose guiding rails 13 are so mounted as to permit of the disposition therebelow of the casters or pulleys 14 carried by the male molding member and the respective limiting lugs 13' and 13'' carried by the tracks 13 as illustrated in Fig. 1.

The frame 15' carries the open auxiliary frame 15 in which is journaled the longitudinally disposed shaft 16 which in turn carries the female mold member 18, the shaft 16 having attached thereto a hand crank 17, by means of which the female mold member may be rotated to entirely reverse its position as shown in Fig. 1 so that the completed molded fabric may be emptied therefrom to fall upon the conveyor 19. The male and female mold members are constructed in the present instance, to form at a single operation, a plurality of the matrices M, clearly shown in Fig. 9. The endless conveyor 19 is mounted upon the power pulley 20 and the guiding pulley 21 and a portion thereof passes through the desiccating or drying chamber 22 so that when the articles are delivered at the end thereof, as illustrated in Fig. 2, the fabricated material is completely dried and is ready for use.

In order that air may be supplied to operate the respective motors 5 and 8, the two supply pipes 23 and 24, having mounted therein the manually controlled valves 25

and 26, are provided. The valve 25 controls the supply and exhaust of the air through the pipes 27 and 28 to the cylinder 5 while the valve 26 controls the supply and exhaust of the air to the cylinder 8. Thus an operator standing upon the platform 55 has complete control of the valves 25 and 26, and the valve 53, the purpose of which will later appear.

The male mold member is provided with 75 the detachable cover 39, which provides between it and the surface of the casting 43, the main chamber 40, there being a plurality of chambers 44, formed by the respective flanges 41 and 42 projecting from the under 80 side of the plate or casting 43, which are in communication with the chamber 44 through the port 45. This chamber 44 is sealed by the plate 46, which carries a plurality of air 85 inlet and air directing funnels 47, the detail of which is clearly shown in Figs. 7 and 8.

Sealing the lower end of the chamber 44 below the partition or wall 46, is a perforated 90 molding fabric or sheet 48, which in the present instance is formed with a plurality of cup shaped members 49 which produce the cup shaped portions 33 of the completed fabric M with the ventilating recesses 35 compressed in the flat surface 34 thereof, or as particularly shown in Fig. 9. 95

The female member 18, as clearly shown in Fig. 6, is provided with a plurality of recessed portions 32 disposed to receive the perforated cup shaped members 49 of the male member, said female member being 100 further provided with the recessed portions 36 which carry the flat springs 37 which in turn receive the projecting ribs 51 of the male member to cushion the action thereof as the male member engages the female 105 member at the primary molding operation, said springs imparting a slight separating movement to the male member, it having been determined in practice one thirty-second of an inch, the purpose of which will 110 later appear.

Carried by the male member are a plurality of guiding lugs or arms 38 which insure the proper registration of the male and female members when the male member is 115 lowered down into contact with the female member. The male molding member or sheet 48 is attached to the under surface of the male molding member by means of the screws 50, which in turn also secure the ribs 120 51 to the under surface of the male member.

In order that air may be supplied to and removed from the chamber 40 and consequently the auxiliary chamber 44 of the present invention, a connection 40^a is provided for the chamber 40 and to it is connected the hose 40^b which in turn is connected to be controlled by the single valve 53, which either admits of a suction through the pipe 52 or pressure through the pipe 54. 130

The suction is employed, when the male member 2 is in the position, as shown in Fig. 1, and is lowered into the vat so that the fabric receiving portion 48 thereof will be submerged. Thus the suction action will cause the pulp to adhere to the surface thereof, so that when the male member is elevated to the position as shown in Fig. 1, and moved to the position to be above and to finally register with the female molding member as viewed in Fig. 6, that the material will be properly compressed therebetween to finally produce the fabric, as illustrated in Fig. 9.

15 It has been found in practice, that it is a difficult matter to separate the cup shaped portion 33 of the fabricated material upon the exterior surface of the cup members 40 of the male mold; various methods of prying and pulling have been resorted to with only fair results.

With the present invention, the air is directed so as to impinge the walls of the inner surface of the cup-shaped portion 49 of the fabric molding portion of the mold, the male member having been elevated only a short distance from the female member; it having been predetermined in practice that one thirty-second of an inch is sufficient, so that 30 the fabric is readily loosened from the male member and will fall by gravity into the female member. It has also been found that the air pressure must be so regulated that too great pressure will be avoided.

35 In order to accomplish this, in the upper end of each air directing member or funnel 47 there is provided an opening 57 in which is mounted loosely and for sliding movement, the stem 58 carrying upon its lower end, the air deflecting disk 59 which is disposed to be in close proximity to the inner wall of the funnel member 47 to cause the air blast to be directed along the walls thereof to finally impinge at a point substantially in line therewith or as indicated by the arrows in Fig. 6, and at which point the air passes through the perforations of the cup shaped member 49 of the male mold and causes the fabric to be slightly separated 45 outwardly therefrom and out of contact therewith so that when the male mold member is elevated and the pressure has been cut off, the fabricated material will remain in the female mold.

55 In order to regulate the amount of air passing in this manner through the directing member 47, there is attached to the upper end of the stem 58 above the member 47, a disk valve 60, the same being perforated at 60 61 to be carried upon the members of the frame 62 which is attached to and extended above the air directing member 47. Thus when the air pressure is too great, the disk 59 is moved downwardly by the pressure and 65 seats the disk 60 upon the top 56 to close the

opening 57 therethrough so that the air pressure is cut off from passing through the air directing member 47. In order to maintain the disk 59 and the disk 60 in neutral position or with the disk 59 out of contact with the inner wall of the air directing member 47 and the disk 60 above and out of contact with the top 56, the balancing spring 63, as illustrated in Fig. 7 is employed. In order to limit the upward movement of the disk 60 and thereby prevent the disk 59 from closing the air directing member when the device is being operated by suction, the limiting means 64 is disposed in the path thereof.

In order that the present invention may be more completely understood, the operation of forming fabricated material from the pulp, which may be a wood pulp or a news-paper pulp, will be fully set forth.

Presupposing that the male member 2 has been moved downwardly due to the operation of the motor 5 so that the same is presented within the vat 1 with the fiber receiving portion of the male member submerged, the valve 53 is moved so that the suction pipe 52 is placed in communication with the pipe 40^b; at which time suction is created within the chambers 40 and 44 and through the air directing member 47 upon the interior of the male mold 48. The same being perforated, the pulp is caused to adhere to the outer surface thereof. The suction valve 53 is now, or may be closed after the mold has been slightly withdrawn, the valve 25 being operated so as to cause the motor 5 to elevate the mold 2 which assumes the position as shown in Fig. 1, with the pulleys or casters 14 in engagement with the rails 13. With the parts in this position, the valve 26 is operated so as to cause the truck 6 to be moved from left to right, as viewed in Fig. 1, and consequently place the male mold 2 in the position directly above the female mold 18. The valve 26 is now closed, and the valve 25 manipulated to permit the motor 5 to lower the male mold 2 so that the cooperating members thereof will cooperate with the female mold, the weight of the male mold being sufficient to compress the fabricated material to the desired thickness, the spring 36 receiving the full jar and also at the same time imparting a slight upward movement to hold the male member separated from the female member.

With the male mold thus held separated from the female mold, thus leaving a space between the lower surface of the fabricated material and the female mold of approximately one thirty-second of an inch, the valve 53 is manipulated to place the pipe 54 in communication with the pipe 40^b, thus causing air pressure instead of the suction action within the chamber 40, and air is forced through the respective ports 45 to 120 125 130

the air directing members 47 which in turn direct the air outwardly and against the inner surface of each of the respective cup shaped portions 49 of the male mold at such a point as to not suddenly but easily remove the fabricated material from the exterior surface of the male mold; and as it has such a short distance to move, one thirty-second of an inch, the same is permitted to rest 10 within the female mold member, so that the instant the valve 53 is moved to neutral, and the air pressure is cut off, the valve 25 may be again operated to elevate the mold member while the motor 8 will also be operated to return it to the position, as shown in Fig. 1. With the parts in this position, the handle 17 is now manipulated to impart a half rotation to the female mold member 18, causing the full release of the fabricated 20 material which falls by gravity, with the cup shaped portions 33 upwardly, to rest upon the conveyer belt 19. As the belt is moving at a slow speed, the material is not injured and is finally passed through the 25 drying drum 22 and is delivered in a thoroughly desiccated or dried condition after having passed therethrough.

What is claimed is:

1. A molding apparatus including a foraminous hollow male mold member having an open end, and means for directing an annular blast of air against the inner surface of said mold member adjacent the open end thereof and in the general direction of 35 the other end of the mold member.

2. A molding apparatus including a hollow foraminous mold member having an open end, a flared nozzle opening into said end portion thereof, and means within the 40 nozzle for directing air under pressure along the wall of the flared nozzle and against the foraminous mold adjacent the open end thereof and in the direction of the other end of the mold.

3. A molding apparatus including a vat, a receiving mold, a hollow foraminous mold having an open end and insertible into the vat, means for creating a suction through the foraminous mold to cause pulp to adhere 50 to said foraminous mold while in and while moving from the vat, means for lowering

the foraminous mold into the receiving mold during the maintenance of suction, and means for successively stopping the suction and directing air under pressure into the 55 open end of the foraminous mold and against the wall of the mold adjacent said end and toward the other end of the mold to strip the molded object into the receiving mold.

4. A molding apparatus including a receiving mold, a hollow foraminous mold, means for creating a suction through the foraminous mold to cause pulp to adhere thereto while the mold is in transit, and a means for reversing the air pressure in the 60 foraminous mold to strip the molded object therefrom and into the receiving mold, said means including a flared nozzle opening into one end portion of the foraminous mold and means within the nozzle for directing air 65 under pressure along the wall of the flared nozzle and against the foraminous mold at one end thereof and in the direction of the other end of the mold.

5. A molding apparatus, including a material holding vat, a male mold mounted for movement into and above the vat and for horizontal movement therefrom, a pivotally mounted female molding member disposed to coöperate with the male molding member and for receiving the molded material from the male molding member, conveying means for receiving the molded material from the female molding member, and means for drying the material in transit.

6. A molding apparatus, including a male and a female mold, the male mold being hollow and provided with a perforated receiving surface, an air directing means mounted in the mold for directing the air to and 90 from the perforated portion, and means mounted in the air directing means for limiting the flow of air under pressure there-through toward the mold.

In testimony that I claim the foregoing as my own, I have hereto affixed my signature in the presence of two witnesses.
